HEAT EXCHANGER HOUSING FOR TELEVISION CAMERAS AND THE LIKE

Thomas Olaf Buck, 730 Blaney Drive,
Dyer, Ind. 46311

Filed Dec. 28, 1967, Ser. No. 9,958

Term of patent 14 years

U.S. Cl. D61—1

Int. Cl. D14—01

FIGURE 1 is a front elevation of heat exchanger housing for television cameras and the like.

FIGURE 2 is a side elevation of FIGURE 1 as viewed from the right side thereof;

FIGURE 3 is a rear elevation of my invention;

FIGURE 4 is a side elevation of FIGURE 3 as viewed from the right side of FIGURE 3;

FIGURE 5 is a bottom view of my invention; and

FIGURE 6 is a top plan view thereof.

I claim:

The ornamental design for a heat exchanger housing for television cameras and the like, substantially as shown and described.
